UNITED STATES PATENT OFFICE.

RAYMOND VERCH, OF ALBANY, NEW YORK.

HEADLIGHT FOR VEHICLES.

1,406,115.

Specification of Letters Patent. Patented Feb. 7, 1922.

Application filed February 1, 1921. Serial No. 441,694.

To all whom it may concern:

Be it known that I, RAYMOND VERCH, a citizen of the United States of America, residing at Albany, in the county of Albany 5 and State of New York, have invented certain new and useful Improvements in Headlights for Vehicles, of which the following is a specification.

My invention relates to headlights for vehicles, and the object of my invention is to provide a powerful non-glaring projecting headlight for use on automobiles, trolley cars, and other vehicles provided with a suitable source of electric energy; a headlight 10 from which the light rays will be emitted in the form of a cone, the topmost rays of which will be substantially horizontal when the device is in normal position; and which is provided with means whereby the light 15 cone may be depressed so as to lie below the normal position; together with such other objects and combinations as may be hereafter set forth and claimed.

I accomplish my objects by means of a 20 headlight arranged and constructed as shown in the accompanying drawings, in which:

Fig. 1 is a vertical longitudinal section.

Fig. 2 is a front elevation with parts 25 broken away.

The same numbers refer to the same parts throughout the views.

My improved non-glare headlight comprises a casing, 2, of any desired shape, but 30 preferably substantially round in cross-section and parabolic in longitudinal section, and provided with raised portions, 20, adapted to be connected to the usual supporting brackets.

35 The inside of the casing, 2, is provided with some suitable dull, non-reflecting finish adapted to absorb rather than to reflect any light rays which may come in contact therewith.

40 Near the rear end of the casing, 2, I provide suitable bearings wherein is adjustably mounted a back reflector supporting shaft, 3, to which the back reflector, 4, is fastened.

Over the open end of the casing, 2, and 45 fastened thereto in any suitable manner, is a face plate, 5, the major portion of the lower half thereof being an opening closed by a plate of glass, 11, through which the light rays are to be projected.

Formed on the inner side of the face plate 55 and near the center thereof, is a shelf, 6, to which are attached the standards, 7, 7, between which is adjustably mounted a suitable reflector, 8, carrying the electric lamp, 9, connected by suitable insulated wires, 60 10, to a source of electric energy.

In the upper half of the face plate, 5, I preferably form a concave recess, 13, adapted 65 to have mounted therein a low candle power electric light, 14, connected by suitable wires, 16, to a source of electric energy. The recess, 13, is preferably provided with a reflecting coating, and covered by a lens, 15.

The operation of my headlight is as follows:

Light rays from the lamp, 9, which is preferably of comparatively high candle power, will be projected against the back reflector, 4, which will deflect the rays and cause them to be projected horizontally or 75 downward through the glass, 11.

I do not wish to limit myself to the particular type or shape of reflectors illustrated in the drawings, as many modifications may be used without departing from 80 the spirit of this invention. A different type of back reflector may be substituted for the reflector 4, as for instance one which will cause most of the light rays reflected thereby to travel substantially parallel to 85 each other; and by using a back reflector having a suitable curved surface the rays may be deflected in almost any desired direction.

I claim:

A headlight for vehicles comprising a casing having a reflector adjustably mounted in the rear end thereof and means for adjusting said reflector from outside the casing; a face plate over the open end of said casing and having an opening through the lower half thereof said opening covered by a sheet of glass, and a recess formed in the face of the upper half of said face plate; a shelf on the inner side of the face plate, 95 an electric lamp with a reflector mounted above said shelf; and a second electric lamp mounted in said recess.

In testimony whereof I have affixed my signature.

RAYMOND VERCH.
